CLOTHING DISPLAY FIGURE

Blanche Erdmann, Paris, France

Application July 20, 1956, Serial No. 42,313

Term of patent 3½ years

(Cl. D80—8)

FIG. 1.

FIG. 2.

FIG. 3.

FIG. 4.

Fig. 1 is a front perspective view of a clothing display figure, showing my new design;

Fig. 2 is a top plan view thereof;

Fig. 3 is a front elevational view; and

Fig. 4 is a side elevational view.

The characteristic feature of my design resides in the base portion of the clothing display figure.

I claim:

The ornamental design for a clothing display figure, substantially as shown and described.
